UNITED STATES PATENT OFFICE

148,582

DESIGN FOR A FLASHLIGHT OR LIKE ARTICLE

Fred Schlotterbeck, New York, N. Y., assignor to Guth, Stern & Co. Inc., a corporation of New York

Application November 12, 1946, Serial No. 134,723

Term of patent 14 years

(Cl. D48—24)

To all whom it may concern:

Be it known that Fred Schlotterbeck, a citizen of the United States and resident of New York city, in the county of Queens, State of New York, has invented a new, original, and ornamental Design for a Flashlight or like article, of which the following is a specification, reference being had to the accompanying drawing, forming part thereof, in which Fig. 1 is a side elevational view of a flashlight showing my new design. Fig. 2 is a front elevational view showing the top end thereof and Fig. 3 is a rear elevational view showing the bottom end thereof.

I claim:

The ornamental design for a flashlight or like article, as shown.

FRED SCHLOTTERBECK.
